(57) **CLAIM**

An ornamental design for a cellular telephone holder, as shown.

DESCRIPTION

FIG. 1 is a perspective view of the cellular telephone holder showing my new design;

FIG. 2 is another perspective view of the cellular telephone holder of FIG. 1;

FIG. 3 is another perspective view of the cellular telephone holder of FIG. 1;

FIG. 4 is a front elevational view thereof;

FIG. 5 is a rear elevational view thereof;

FIG. 6 is a right elevational view thereof;

FIG. 7 is a left elevational view thereof;

FIG. 8 is a top plan view thereof; and,

FIG. 9 is a bottom plan view thereof.

The broken line showing of environment in the drawings is for illustrative purposes only and forms no part of the claimed design.
